(57) **CLAIM**

The ornamental design for an adjustable wand for a vacuum cleaner, as shown and described.

DESCRIPTION

FIG. 1 is a right-side perspective view of an adjustable wand for a vacuum cleaner showing our new design;

FIG. 2 is a front view thereof;

FIG. 3 is a back view thereof;

FIG. 4 is a left side view thereof; and,

FIG. 5 is a right side view thereof.

The broken lines are included for the purpose of illustrating the unclaimed portions of the article and form no part of the claim.

1 Claim, 3 Drawing Sheets
